(57) **CLAIM**

The ornamental design for a chest protector slip-on member,
as shown and described.

DESCRIPTION

FIG. 1 is a perspective view of a chest protector slip-on member showing our design;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof;

FIG. 8 is a front view of the chest protector slip-on member attached to a chest protector; and,

FIG. 9 is a perspective view of the chest protector slip-on member attached to a chest protector.

The broken line showing of FIGS. 1, 4, 8 and 9 are for environmental purposes only and form no part of the claimed design.

1 Claim, 3 Drawing Sheets
